UNITED STATES PATENT OFFICE.

RAY W. SCOTT, OF NEW YORK, N. Y., ASSIGNEE TO NEW YORK ATTACHABLE PLAYER ACTION CO., A CORPORATION OF NEW YORK.

PLANO.

1,086,408.

Specification of Letters Patent. Patented Feb. 10, 1914.

Application filed September 18, 1910. Serial No. 531,895.

To all whom it may concern:

Be it known that I, RAY W. SCOTT, a citizen of the United States, residing at New York city, in the county of New York and

5 State of New York, have invented certain new and useful Improvements in Pianos, of which the following is a specification, reference being had therein to the accompanying drawing.

10 My invention relates to improvements in automatic piano players and has particular reference to the manner of constructing and attaching the pneumatics and other operating mechanism. The pneumatics are preferably of about the same width as the piano keys and are preferably so mounted that they may be readily attached to or removed from the ordinary manually operated piano.

Referring to the accompanying drawings, 20 Figure 1 is a partial sectional view of a piano illustrating an application of my invention. Fig. 2 is a plan view partly broken away illustrating the music roll mechanism, more particularly set forth and 25 claimed in my co-pending application Serial No. 742414, filed January 16, 1913, and Fig. 3 is a plan view partly broken away illustrating some of the keys and pneumatics in position.

30 4 is the key bottom provided with suitable bearings 5 and 6 to hold the key 7 in position, and 8 is the front board of the piano. 9 is a portion of the regular piano action and 10 is the usual action rail.

35 11 is the usual key slip.

12 is the wind-way preferably running the entire length of the key board and by means of which the air is exhausted from the various pneumatics.

40 13 is a suitable bar also preferably running the entire length of the key board for supporting the front ends of the pneumatics. The pneumatic 14 is preferably provided with an inclined front section as shown and

45 15 is normally open to the atmosphere through the cut 15 and slot 16 so that when at rest the pneumatic and key are in the position shown in Fig. 1. The operating connection between the key 7 and the pneumatic 14 is

50 represented by the cord 17 which is fastened to the top of the pneumatic, then passes through an aperture in the bottom board 4, thence through the cleat 18 and the aperture 19 of the key 7 where the other end 55 is fastened around the screw 20. While in

this position air is drawn through the tube 21 from the wind-way 12 which exhausts each pneumatic through the cut 22 and the chamber 23.

24 is a tube which connects with the 60 tracker board 25 so that when a perforation in the sheet of music 26 allows air to enter the tube 24 through said tracker board, it passes to the primary pneumatic 27 thereby causing the same to inflate under influence 65 of the vacuous condition in the chamber 23 thereby elevating the post 28 secured to the top of the primary pneumatic 27 and causing the valve 29 to lift from its seating. This allows the suction to operate through 70 the cut 15 from the pneumatic 14 which causes the top 30 to descend pulling upon the cord 17 and causing the key 7 to raise the action 9. After the perforation in the sheet of music 26 has passed the perforation 75 in the tracker board 25 and air no longer enters the tube 24, the air remaining in the tube 24 is drawn off through the bleed hole 31 and the post 28 again descends as the bag 27 deflates thereby allowing the valve 80 29 to become reseated thus reestablishing the normal condition. It will be observed that when the valve 29 is raised and the pneumatic is in operation, the air drawn through the suction is cut off from the slot 85 16 communicating with the atmosphere and that the pneumatic 14 is again brought into communication with the atmosphere through the slot 16 as soon as the valve 29 becomes 90 reseated. In other words, when the pneumatic is deflated the cord pulls the key down, and when the pneumatic is inflated the key returns to its normal position. In order to adjust the length of the cord 17, it is only necessary to remove the front 95 board of the piano and the stroke of any key may be adjusted by tightening or loosening the cord 17 around the screw 20. As far as I am aware it is new in the art to provide this means of adjustment. The 100 pneumatic itself is designed and built along novel lines. To the best of my knowledge it is new in the art to provide a pneumatic of the same width as the width of the key, and also so arrange it that repairs can easily be made and further to provide means whereby I am enabled to position the pneumatics under the keys in such fashion that ample room is left for the other parts of the 105 player mechanism and also for the legs of 110

the operator, when the keys are operated manually.

The pneumatics may be connected by a suitable rod such as 32 and may be secured 5 to the wind-way and key bottom 4 by screws such as 33 or in any other suitable manner. The front of each pneumatic is also preferably secured to the rod or bar 13 by a screw such as 34. From this arrangement it will 10 be understood that the pneumatics may be placed in position and removed collectively or by withdrawing the rod 32 may be attached and removed separately.

35 and 35^a are brackets secured to the 15 front and back pneumatic supports carrying the rack 36. This rack carries the frame 37 which is adapted to slide thereupon and which is provided with bearings 38-38^a having arms such as 39-39^a and pinions 20 such as 40-40^a, so that as the arm 39 is swung outwardly and downwardly upon the bearing 38, the frame 37 is caused to recede beneath the front of the piano.

41 and 42 are the usual spools upon which 25 the perforated music is mounted. The music is preferably taken off the spools before the framework is turned beneath the piano as stated.

44 is a vertical slot or guide cut in the bar 30 13 to receive the projection 43 which may be suitably secured to the top 30 of the pneumatic. This serves to guide the movement of the pneumatic when in operation. The front ends of the lower portion of the 35 pneumatic are also preferably terminated in forks such as 45. This permits of a little adjustment and at the same time is convenient in attaching and removing the pneumatics.

40 It will be seen that everything below the key bottom may be removed by withdrawing the screws 33 and 34. Of course the screws 34 need not all enter the key bottom 4. The majority of them may be much shorter simply to hold the end of the pneumatic and the same applies to the screws 33. It is not necessary that these screws should be so long as to penetrate the key bottom 4, the preferred form of construction being to

make the wind-way 12 and the bar 13 serve 50 as a frame for the pneumatics so that by loosening a few of the longer screws 33 and 34, everything below the key bottom may be removed, it being understood that the front board 8 has been previously removed 55 and the screws 20 loosened from the cords 17.

Of course it will be understood that various modifications may be made without departing from the spirit of the invention as set forth in the claims.

Having described my invention, what I claim as new, and desire to secure by Letters Patent, is:

1. In an apparatus such as described, keys, pneumatics to operate the same, means 65 for operatively supporting said pneumatics in a single row beneath and in line with said keys, said pneumatics having an inclined front section, and a spool frame secured parallel to said inclined front section. 70

2. In an apparatus such as described, keys, pneumatics to operate the same, means for operatively supporting said pneumatics beneath said keys, said pneumatics having an inclined front section, and a spool frame 75 secured parallel to said inclined front section and being adapted to swing downwardly and rearwardly beneath the same.

3. In an apparatus such as described, keys, pneumatics to operate the same, means 80 for operatively supporting said pneumatics in a single row so that each of said pneumatics are beneath and are in a vertical line with said keys, said means comprising front and back supports, cords connecting said 85 pneumatics and said keys, each of said cords secured forward of the center of the top of the key and passing through the same to a point at the front and below the key to the forward movable portion of the pneumatic 90 beneath the same.

In testimony whereof I affix my signature in presence of two witnesses.

RAY W. SCOTT.
